UNITED STATES PATENT OFFICE.

CARL H. BISSELL, OF SYRACUSE, NEW YORK, AND DANIEL C. GIDLEY, OF BOSTON, MASSACHUSETTS, ASSIGNORS TO CROUSE-HINDS COMPANY, OF SYRACUSE, NEW YORK, A CORPORATION OF NEW YORK.

DESIGN FOR AN ELECTRICAL-CONDUIT OUTLET-BOX.

47,987.

Specification for Design.

Patented Oct. 19, 1915.

Application filed July 30, 1915. Serial No. 42,838. Term of patent 14 years.

To all whom it may concern:

Be it known that we, CARL H. BISSELL, a citizen of the United States, residing at Syracuse, in the county of Onondaga and State of New York, and DANIEL C. GIDLEY, a citizen of the United States, residing at Boston, in the county of Suffolk and State of Massachusetts, have invented a new, original, and ornamental Design for Electrical-Conduit Outlet-Boxes, of which the following is a specification, reference being had to the accompanying drawing, forming a part hereof.

In the drawing, Figures 1, 2 and 3, are respectively, a plan, side elevation and end elevation of a conduit outlet box showing our new design.

This conduit outlet box presents in plan the appearance of a cylindrical stem a terminating in an elliptical end of a length and width greater than the width of the stem, and in side elevation the appearance of two cylindrical bodies a, b of unequal diameter meeting at an angle.

Copies of this patent may be obtained for five cents each, by addressing the "Commissioner of Patents, Washington, D. C."

What we claim is:

The ornamental design for an electrical conduit outlet box substantially as shown and described.

In testimony whereof, CARL H. BISSELL, has hereunto signed his name in the presence of two attesting witnesses, at Syracuse, in the county of Onondaga, and State of New York, this 15th day of July, 1915, and DANIEL C. GIDLEY, has hereunto signed his name in the presence of two attesting witnesses, at Boston, in the county of Suffolk, and State of Massachusetts, this 21st day of July, 1915.
